UNITED STATES PATENT OFFICE.

CHARLES A. MURDOCH, OF NEW YORK, N. Y.

COMBINED SINK AND DISHWASHING MACHINE.

Refiled for abandoned application Serial No. 596,328, filed October 23, 1922. This application filed May 21, 1925. Serial No. 31,970.

My invention relates to machines for washing and sterilizing dishes, china, cutlery, silverware, and the like, and more particularly to a machine of this character that may be also utilized in place of, and as a substitute for, the ordinary sink for houses and apartments.

In my copending application Serial No. 31,971, filed May 21, 1925, for household washing machines, I have described and claimed an improved machine for washing and sterilizing dishes and the like, including an improved top spray for such machines. Because of the construction of such improved washing machine, it is impossible to utilize the same in its present condition as a substitute for the ordinary kitchen sink, and, further, while the form of top spray therein shown and described is efficient, it very often happens that it is desirable to employ a spray that will deliver more water than is possible in such a machine. The present invention, comprises a washing machine capable of being used as a substitute for a kitchen sink, performing either of the functions of a dish washer or a sink, although not both functions simultaneously.

In a dish washing machine of the character disclosed in the present invention, the water level in the washing tank need not be excessively high, and, in fact, it is better that the tank be not over one quarter full as it is found that the dishes are more successfully washed, cleansed and sterilized if they are located in what is really a vapor chamber, the watering fluid seeming to wash more efficiently if the water flows over the dishes rather than to have the dishes set in a large volume of water. In a sink, it is often advisable to fill the same entirely full of water. An object of the present invention is the provision of an improved means for maintaining, at will, different levels of water in a tank that is suitable for use as a dish washing tank and as an ordinary sink.

In the accompanying drawings illustrating the preferred embodiment of my invention

Fig. 1 is a front elevation;

Fig. 2 is a side elevation partly in section;

Fig. 3 is an enlarged detail view of the bottom portion of the tank and parts carried thereby, certain portions of the same being shown in section;

Fig. 4 is a sectional detail elevation of the connection between the upper cover manifold and the water delivery pipe;

Fig. 5 is a sectional detail view of the automatic valve leading from the pump and which prevents flow of water from the main supply pipe when the apparatus is to be utilized as an ordinary kitchen sink;

Fig. 6 is a detail view, partly in section, showing a means for operating the electrical connections leading from the supply means to the pump driving motor, and

Fig. 7 is a detail view, partly in section, showing a modification of the upper spray manifold.

Referring to the drawings, 10 designates a shallow basin substantially rectangular in shape and to each corner of which is secured by bolts 11 legs or supports 12. Fitting into the top of the basin 10 and secured thereto by rivets 13 and by soldering, or in any other suitable manner, is a sheet metal drum 14 of any suitable height and to the top of this drum 14 is secured by rivets 15, or in any other suitable manner, a metallic ring 16, the ring 16 forming the upper edge or rim of the basin or tank comprised of the members 10, 14 and 16. Formed integral with, and depending downwardly from, the bottom of the basin 10 is a chamber 17, one side of which is provided with an opening 18 and to this side of the chamber 17 and surrounding the opening 18 is a pump chamber or cylinder 19 having rotatably mounted therein the impeller 20. Extending outwardly from the chamber 19 on the side remote from the chamber 17 is a hollow bearing 21 the outer end of which is threaded and has secured thereon the packing nut 22. Loosely fitting in the hollow bearing 21 and secured therein by screws 23 is a bearing collar 24 of any well known anti-friction metal, and rotatably mounted in this bearing collar 24 is a shaft 25 formed integral with, or secured to, the impeller 20. This shaft 25 is threaded at 26 to receive a packing nut 27 and by means of the bearing collar 24 is forced into close association with the outer end of the impeller 20. Surrounding the shaft 25 exterior of the nut 27 and interior of the packing nut 22 is the usual packing material 28. With the construction just described, I obtain a bearing for an impeller 20 that is self-centering anti-friction in that it needs no lubrication,

105
110

and water-tight and one in which there is a three sided bearing surface for the shaft 25 and impeller 20.

Secured to the outer end of the shaft 25 by pins 29 is one element of a flexible joint 30, the other element of this joint 30 being secured by pin 31 to one end of the shaft 32 of an electric motor or other device 33 which is secured by bolts 34 to bosses or 10 projections 35 formed on the lower or bottom surface of the basin 10.

The chamber 17 connects with the basin 10, and at the upper portion of this chamber 17 is provided a screen or sieve 36 in 15 which collects garbage, grease, etc., that may be washed from the dishes, cutlery, or the like, located in the washing chamber. To the exit end of the pump above described is connected one end of a pipe or conduit 20 37, the other end of which is secured in any suitable manner to the bottom of a modified T or elbow 38, and within this modified T or elbow and cooperating with a packing ring 39 therein is a pivotally mounted flap 25 valve 40 which prevents entrance of fluid to the pipe or conduit 37 toward the pump, but does not prevent exit of fluid from such pipe. On the rear of the device the wall of the base 10 is provided with an orifice 30 through which extends the threaded end 41 of the intermediate portion of the modified T or elbow 38, and on this threaded end is screwed a ring 42 for making a tight joint between the casing 10 and the modified T 35 or elbow 38. A passage through the threaded end 41 connects the interior of the modified T or elbow 38, and therefore the pipe or conduit 37, with the interior of the chamber formed by the members 10, 14 and 16. 40 Threaded into an opening into the top of the modified T or elbow 38 is the lower end of a water distribution pipe or conduit 43 which extends upwardly to a point adjacent to the member 16 and to the top end is 45 secured an elbow 44, the other end of this elbow being secured to the member 16 by bolts 45, an orifice 50 being provided in the rear portion or wall of the member or ring 16 communicating with the elbow. Located 50 to the rear of the device and preferably forming part of the drain board of the combined washing machine and sink is a member 46 to the front edges of which is pivotally mounted by hinges 47 a cover 48 provided on its interior surface with a depending ring 49 of the same shape as the interior of the ring or member 16 and of such size as to fit within said ring or member 16, as clearly shown in Fig. 2. The rear portion 55 of this depending ring 49 accommodates the orifice 50 that communicates through the opening in the ring or member 16 with the elbow 44. Secured to the lower interior edge of the depending ring 49 is a sheet 60 metal member 51 spaced apart from the de-

pending member 49 and the inner surface of the cover 48 to define thereby a manifold consisting essentially of an encircling chamber 52 and a central chamber 53, the member 51 being provided with a plurality of 70 perforations as 54 through which water or other washing liquid may be forced. It is obvious from the above description that, if water is forced through the pipe or conduit 37 by means of an impeller 20 of the pump, 75 such water or other fluid will be forced through the member 41 into the lower part of the chamber formed by the members 10, 14 and 16 and will also be forced upward through the pipe 43 and elbow 44 into the 80 chamber formed by the cover 48 and inner member 51 and such water or other fluid will be forced downwardly through the perforations 54 in the form of a spray. The hollow threaded member 41 of the modified T or elbow 38 is of such shape as to receive the end of a manifold comprised essentially of a pipe 55 having connected thereto a plurality of laterally extending perforated pipes 56, the perforations in such pipes being on an upper portion thereof so as to direct a spray of water or other washing liquid upwardly in the tank composed of the members 10, 14 and 16. The manifold composed of the pipes 55 and 56 may readily be removed from the hollow portion 41 when it is desired to utilize the apparatus as an ordinary sink, by withdrawing the end of the manifold from the member 41. Secured to the rear portion of the ring 16 is a control switch 57 having a plunger forming part thereof extending through the member 16 and into the path of movement of a boss 58 formed on the depending ring 49 that is attached to the cover plate 48. This control switch 57 is connected with any suitable source of power (not shown) and in the usual manner with a motor 33. As the manner in which such connections are made is not important as far as concerns the 110 present invention, they have not been shown and will not be further described. 105

Screwed into the modified T or elbow 38 intermediate its top and bottom and connecting with the interior thereof is one end 115 of a supply pipe 60, the other end of which is screwed into a T 61 provided with a stop plug 62 and having screwed into the upper T portion thereof the lower end of a supply pipe 63, the upper end of this supply pipe 120 being screwed into a T 64. To the other end of the T is screwed a pipe 65, the other end of this pipe being screwed into one end of a valve 66 which is connected to a source of water supply, as a hot water supply by a pipe 67. To the T portion of the T 64 is secured by nipple 68 an elbow 69 which is connected by pipe 70 to a valve 71 connected to a source of water supply, as a cold water supply, by a pipe 72. 130

Located at the rear of the apparatus and passing through the backboard 46 is a standpipe 73 provided at its lower end with a connecting T 74 to the lower end of which is screwed a drain pipe 75 and screwed into the T portion 74 is one end of a pipe 76 which extends to a point under the tank 17 and is connected thereto by means of an elbow 77. The standpipe 73 is connected to the tank formed of the members 10, 14 and 16 at a plurality of points which points determine the water level it is desired to maintain in such tank, the lower water level being defined by a pipe 78 extending between the tank and the standpipe 73 and another point defining the highest water level it is desired to maintain in the tank defined by the pipe 79 extending between the tank and the standpipe 73. Within the T 74 and above the upper end of the drain 75 is a valve seat 80 which cooperates with a disk valve body 81 secured around the lower open end of a pipe or stem 82 which extends upwardly through the standpipe 73 and has secured to its upper end a knob or handle 83. This pipe 82 is provided with an elongated slot 84 in alignment with, or in the same horizontal plane as, the connecting pipe 78 and with an elongated slot 85 in alignment with, or in the same horizontal plane as, the connecting pipe 79. Rotatably mounted on the pipe 82 is a pipe or tube 86 which has secured to its upper end a knurled ring 87 and by means of which the pipe or tube 86 may be rotated. This pipe or tube 86 is provided with a slot 88 which may be brought into registry with the elongated slot 84 and thus provide an exit for fluid downward through the pipe 82 and into the drain 75 even though the valve 81 is on the valve seat 80, and by maintaining the slots 88 and 84 in registry, the water level in the tank is predetermined. Also the pipe or tube 86 is provided with a slot 89 that may be brought into registry with the slot 85 in the pipe or tube 82 and preferably the position of the slots 89 and 85 with regard to the position of the slots 88 and 84 is such that the slots 89 and 85 will be in registry when the slots 88 and 84 are out of registry thereby making it possible to have the level of liquid in the tank comprised of the members 10, 14, and 16 maintained at the connecting tube 79.

From the above, it will be obvious that I may utilize the apparatus shown on the drawings and herein described as a dish washing machine which requires that the water be maintained at a low level within the tank by filling the water chamber 17 and the lower part 10 of the tank up to a point determined by the tube 78 and may circulate such water by means of the impeller 20 of the pump through the manifold comprised of the pipes 55 and 56 and

through the upper spray cover manifold, including the spray chambers 52 and 53, such pump, however, not being operable until the break point in the circuit of electric motor 33 is closed by the boss 58 on the member 49 engaging with the plunger of the control switch 57. It will also be apparent that I may utilize the apparatus as a substitute for the ordinary kitchen sink and may either maintain the level of fluid therein at the point predetermined by the pipe 78 and the slots 88 and 84 at a low point, such as is found advisable when the device is used as a dish washing machine, or maintain it at a high level determined by the connecting pipe 79 and slots 89 and 85 by rotating the tube or pipe 86 on the pipe 82 so as to throw the slots 88 and 84 out of registry, and I may empty the entire apparatus of fluid by lifting the tube 82 by means of knob or handle 83, thus moving the valve 81 off the valve seat 80.

While I have described the preferred form of down spray, I may substitute for this preferred form the form shown in detail in Fig. 7 wherein the sheet metal member 14 of the tank is secured to a modified form of ring 90, a modified form of cover 91 being employed and the modified form of ring 90 having an inwardly and downwardly extending lip 92 which partially shields a spray manifold 93 provided with a plurality of downwardly directed perforations 94 and this manifold is connected with the pipe 43 by means of an elbow 95. This form of spray manifold is less liable to derangement and possible leakage than the form illustrated in the other figures on the drawings because of the fact that it is connected positively and permanently with the pipe 43 and does not depend for tight fitting on the hinges 47.

While I have shown and described the preferred embodiment of my invention somewhat in detail, it is to be understood that I may vary the size and arrangement of parts within wide limits without departing from the spirit of the invention.

I claim:

1. In a washing machine, a wash chamber, means for circulating a washing liquid therethrough under pressure, a drain pipe leading from the bottom of said chamber, a drain pipe leading from the top of said chamber, a drain pipe leading from said chamber intermediate its top and bottom, a discharge pipe having common connection with all of said drain pipes, a valve movable longitudinally in said discharge pipe for a control common to all of said drain pipes, a hollow stem on said valve and open through the body thereof, said stem having apertures in alignment with the top and intermediate drain pipes, and a sleeve movable over said stem, said sleeve having aper-

tures therein for selective registry with said stem apertures for drainage through said stem when said valve is closed.

2. In a washing machine, a wash chamber, a sump in the bottom thereof, spray means in the top of said chamber, spray means in the bottom of said chamber, a water distribution pipe having a connection adjacent one end with said top spray means and a connection adjacent its other end with said bottom spray means, a water inlet conduit in communication with said distribu-

tion pipe between said top and bottom spray means, a force pump in said sump, an eduction pipe rising from said pump and having 15 communication at its delivery end with said water distribution pipe beneath said water inlet conduit and said bottom spray means, a check valve at the delivery end of said eduction pipe to prevent water from entering said eduction pipe through its delivery end, and a drain pipe leading from the bottom of said sump. 20

CHARLES A. MURDOCH.
